WILLARD G. DAY, OF BALTIMORE, MARYLAND, ASSIGNOR OF TWO-THIRDS
TO WILLIAM F. HOWARD, OF SAME PLACE, AND GEORGE H. HOWARD,
OF WASHINGTON, DISTRICT OF COLUMBIA.

METHOD OF PRESERVING PERISHABLE SUBSTANCES.

SPECIFICATION forming part of Letters Patent No. 593,741, dated November 16, 1897.

Application filed September 14, 1896. Serial No. 605,770. (No specimens.)

To all whom it may concern:

Be it known that I, WILLARD G. DAY, of the city of Baltimore, in the State of Maryland, have invented certain new and useful 5 Improvements in Methods of Preserving Perishable Substances, of which the following is a specification, reference being had to the accompanying drawing and the letters and figures of reference marked thereon.

10 My invention relates to methods of preserving perishable substances through the action of the radiant energy—such as light, heat, and actinic waves—developed by and from an electric current. I have found and demonstrated after careful experiment that the action 15 of the rays from an electric light, either incandescent or arc, on an organic body placed in proximity to it is such that all incipient germs of life, whether of approximately high 20 order, such as life-germs—*e. g.*, those of the egg—or of the low order, such as decay-germs, or germs of the kind which cause putrescence and mold, are killed, or at least rendered less harmful. In brief, this radiant energy has 25 a sterilizing effect. I therefore consider the application of these rays to be highly important in the art of preserving perishable food from the influence of mold and decay. By proximity of the organic body to be acted 30 on to the source of radiant energy is meant that the substance to be preserved is placed in such intimate nearness to the center of energy from which the light, heat, and actinic waves proceed that said energy is capable 35 of being concentrated on said substance in order to produce the desired effect. Therefore there must be such intimacy of relationship between the substance and the source of energy as will produce under all normal conditions the effect or an approximation to the effect desired. Consequently the mere incidental placing of an electric lamp within a room for lighting purposes would not be regarded as resulting in any of the functions 40 45 accomplished by my arrangement, and therefore I have no intention of covering such an incidental arrangement, as such incidental arrangement has no bearing upon my invention.

The apparatus required for this method is 50 a very simple one, being either an incandescent or arc light placed near said substances

or in a chamber or receptacle which may hold these substances, they being acted upon either directly or through slight intervening media. This lamp is supplied with an electric current, either alternate or continuous, which is of the necessary voltage and amperage such as to bring the light to sufficient intensity to perform its work. With this arrangement of apparatus it is preferable to use 55 some form of regulation—such as an ordinary resistance-regulator or rheostat in case of a direct current or inductive resistance in case of an alternating current—so as to bring the light to the intensity proper to perform the desired operation upon any part of the material.

The lamps may be arranged in banks, with reflecting bodies at their backs to concentrate the energy upon the substance to be acted on. Moreover, it is of importance to have a circulation of air passed by and around these substances in order to rapidly carry off the moisture, and therefore it is advisable to artificially dry said air before it is passed around or through these substances. Artificially 70 dried air may be passed in currents through these receptacles by means of an ordinary pumping apparatus, thus passing it along and through the substances in such a way as to quickly carry off all moisture. It has 75 been found by me that it is desirable for efficiency of action that the substances be reduced to such condition—that is, made sufficiently thin—that they can be readily and economically acted on.

Referring to the accompanying drawing, let G represent a generator of electricity, either a direct or alternating current dynamo-machine.

Let L L represent wires extending from 90 said generator to an incandescent lamp A or to an arc-lamp B.

Let 1 and 2 represent, respectively, a receptacle and a holder in or on which the organic perishable substance is placed in proximity to 95 the light. As shown in the drawing, various substances are placed in or on this receptacle—for instance, meats, fish, eggs, vegetables, and other similar organic substances.

R represents a resistance-regulator or rheostat or inductive resistance, which is placed anywhere in the circuit between the source 100

of electrical energy and the lamp. Having raised the potential to the required degree and having attained the desired amount of current in the circuit, we switch the lamp 5 into action and place the substances in or upon the receptacle 1 or 2 and expose them to the continuous action of the rays and heat from the light for any length of time—say from a few minutes or hours up to several 10 days, the period of course depending upon the tenacity of life exhibited by each species of life-germs. It is often the case that the lowest forms of life, such as mold-germs, exhibit the greatest tenacity. Therefore it is 15 well in such cases to expose the material to the direct action of the light for, say, several hours, or even days, as the case may be. Within the receptacle, in which is placed a group of incandescent lamps, preferably in banks, are 20 reflectors situated behind or in proper relation to the lamps, so as to concentrate the rays of light upon the substances to be treated. Instead of reflectors of the mirror type white-painted surfaces may be employed. These 25 mirrors or reflecting-surfaces are, however, not absolutely essential and may be omitted. An air-pump D may supply a current of ordinary air, or preferably artificially-dried air, with a sufficient impetus to pass by and 30 through the substances and carry off moisture, dust, and other injurious deposits. At D' is shown the exit at which the air passes out of the receptacle. The air may, however, be used under natural draft induced by the 35 heat within the receptacle, which under such conditions would have proper means for admission and discharge.

I find that a temperature of about 90° to 40 110° Fahrenheit is that producing the best results, although I have attained good effects under temperatures somewhat lower and higher. I have found this action effective and useful in preserving meats, eggs, milk, and vegetables—in fact, all organic perishable 45 substances.

If an incandescent lamp is used, it is to be clearly understood that the filament is to be of sufficient capacity to carry the necessary current of the proper potential. Therefore 50 it is preferable to have the filament of much higher capacity than the one in an ordinary incandescent light of, say, sixteen to thirty-two candle power. It is much better to use a lamp of, say, from fifty to one hundred 55 candle power, or even more.

It may be necessary under some conditions and in some climates, when it is desired to maintain intact the sterilizing action of the radiant energy or actinic waves produced 60 from the incandescent or arc lamp, that the perishable substances shall be surrounded by a wrapping impervious to decay-germs, either after being acted on by said waves or while being acted on by said waves, and after. For though under certain conditions 65 the action of these rays would be efficient in destroying the germs that are present, yet

their action might not under those conditions protect the substances from future attacks of germs. Therefore a protecting-coating under such conditions is necessary in all cases in which it is desired to keep the substances any considerable length of time uninjured and free from the above-mentioned deteriorating influences. The use of such protecting-coating with substances treated as aforesaid is therefore recommended where such conditions require it and forms part of my invention.

In the practice of my invention, in treating, 80 for instance, meats I have found it advisable to reduce the meat to slices or cuts from half an inch to one inch and a half in thickness, and after treatment, under the conditions hereinbefore mentioned, has been completed to pulverize or grind the material, so as to bring it to convenient condition for packing, shipment, and use. In the use of meat so treated and pulverized it has been found that it may be made, by cooking, into 85 most acceptable dishes for the table by the use, first, of sufficient moisture to restore the article to somewhat of its original condition, and afterward preparing and seasoning it in any way known to the art of cookery. If the 90 meat or other substance is to be used as the basis of a soup, stew, or the like, the previous addition of water or moisture is obviously unnecessary.

Any of the substances treated under my 95 invention and pulverized may, if the form in which they are to be eaten requires it, be before preparation for the table restored to a condition resembling the original one by the addition of water.

The air admitted to the substances while in the presence of the lamps may be filtered by any suitable means to exclude from the substances the deleterious matter ordinarily found in the atmosphere, as well as to exclude 100 flies or other insects, dust, &c. A screen or filtering agent suitable for this purpose is represented by X.

The pulverized material may be conveniently cooked as a solid dish as follows: 115 First supply to a given quantity enough water, or a little more, to restore that lost by evaporation, and allow the mixture to simmer over a fire for a short time until it is reduced to a pulp. Then cook, with the proper constituents and seasoning, as croquettes, hash, Hamburg steak, &c., or in any of the many ways known to the art of cookery. Oysters, 120 crabs, clams, &c., in this form of powder may be deviled or otherwise dished. The 125 mode of preparation of soups, stews, and the like will be evident to the skilful cook.

The product which results from this process differs from all others with which I am familiar in being cured without any cooking 130 action or by the employment of creosote, smoke, salt, or other antiseptic. The application of a powerful electric light in accordance with my method destroys any germs

which may have been within the substance, while the process affects both the exterior and the interior portions of the substance, so as to prevent the entrance of any germs from the outside. The brittleness which may be caused by the curing process renders the substance easily pulverizable at any time after the completion of the process.

I am aware that heretofore electric-light plants—*e. g.*, arc or incandescent—have been installed in stores, markets, storage-rooms, and the like, and that in such stores, markets, and storage-rooms perishable substances have been suspended or stored. Such an arrangement I do not claim, as having no bearing upon my invention, which is strictly limited to the bringing of perishable substances, such as food products, distinctly within the active influence of the waves of radiant energy which are generated by and through the electric light which is in proximity to said substances. In fact, it is an essential feature of my invention to have such juxtaposition of light and substances that the operative effect, which is the gist of my method, can take place. In the proper carrying out of this method, as has been before set forth, suitable regulation of the intensity of the waves of radiant energy is an important factor.

Having thus described my invention, I claim—

1. The method of preserving organic perishable substances, which consists in generating electrical energy, producing by said energy waves of radiant energy, bringing said radiant energy to the required strength and activity, and causing it to penetrate and act upon the perishable substances placed in proximity to the center of action for a sufficient length of time to destroy all germs of decay, substantially as set forth.

2. The method of preserving organic perishable substances, which consists in generating electric currents, carrying said currents to any desired point, producing by said currents, light, heat and actinic waves of energy, bringing said waves to the required strength and activity, and causing them to penetrate and act upon the perishable substances placed in proximity to said point of action for a sufficient length of time to destroy all germs of decay, substantially as set forth.

3. The method of preserving organic perishable substances, which consists in generating electric currents, carrying said currents to any desired point, producing by said currents a focus of radiant energy in, for example, an incandescent or arc lamp, by which light, heat and actinic waves are produced, and causing said waves to penetrate and act upon the perishable substances placed in proximity to said focus for sufficient length of time to destroy all germs of decay, substantially as set forth.

4. The herein-described method of preserving organic perishable substances from decay and deterioration, which consists in produc-

ing by an electric current light, heat and actinic or chemical rays capable of penetrating said substances, and in proximity exposing 70 the same to the penetrative action of said rays for a sufficient length of time to accomplish the required result.

5. The method herein described of preserving organic perishable substances from decay 75 and deterioration, which consists in producing by an electric current heat, light and actinic or chemical rays, capable of penetrating said substances, in proximity exposing the same to the penetrative action of said rays, 80 and regulating the amount of electrical energy in accordance with the demand, and subjecting said germs to said action for such time as is in accordance with the strength of the germs to be destroyed in each particular case. 85

6. The method of preserving organic perishable substances from decay, which consists in producing by an electric current, light, heat and actinic or chemical rays, capable of penetrating said substances, and in proximity exposing 90 said substances to the penetrative action of said rays for a sufficient length of time to accomplish the required result, and enveloping the said substances in a germ-protecting covering so as to prevent new access of 95 germs to said substances, substantially as set forth.

7. The method of preserving organic perishable substances, which consists in generating electric currents, carrying said currents 100 to any desired point, producing by said currents light, heat and actinic waves of energy, bringing the said waves to the required strength and activity, and causing them to penetrate and act upon the perishable substances placed in proximity to said point for 105 a sufficient length of time to destroy all germs of decay, and subjecting said substances, while under the influence of said currents, to a circulation of air for carrying off therefrom 110 the moisture liberated by the heat energy of said electric currents, substantially as set forth.

8. The method of preserving organic perishable substances, which consists in generating electric currents, carrying said currents 115 to any desired point, producing by said currents light, heat and actinic waves of energy, bringing the said waves to the required strength and activity, and causing them to 120 penetrate and act upon the perishable substances for a sufficient length of time to destroy all germs of decay, and subjecting said substances, while in proximity to and under the influence of said currents, to a circulation 125 of artificially-dried air for carrying off therefrom the moisture liberated by the heat energy of said electric currents, substantially as set forth.

9. The method of preserving organic perishable substances, which consists in generating electric currents, carrying said currents to any desired point, producing by said currents light, heat and actinic waves of energy,

bringing the said waves to the required strength and activity, and causing them to penetrate and act upon the perishable substances for a sufficient length of time to destroy all germs of decay, and subjecting said substances, while in proximity to and under the influence of said currents, to a circulation of artificially-dried and filtered air for carrying off therefrom the moisture liberated by the heat energy of said electric currents, substantially as set forth.

10. The herein-described method of producing an article of food, which consists in subjecting the food substance placed in proximity to the radiant energy of electric currents, utilizing therefrom the light, heat and actinic waves produced thereby, and carrying off the moisture liberated by the heat energy of said currents, substantially as set forth.

11. The method of producing an article of food, which consists in subjecting the food substance placed in proximity to the radiant energy of electric currents, utilizing therefrom the light, heat and actinic waves produced thereby, carrying off the moisture liberated by the heat energy of said currents, and finally pulverizing or grinding said substance, substantially as set forth.

12. The method of producing an article of food, which consists in subjecting the food substance placed in proximity to the radiant energy of electric currents, utilizing therefrom the light, heat and actinic waves produced thereby, carrying off by artificially-dried air the moisture liberated by the heat energy of said currents, and finally pulverizing or grinding said substance, substantially as set forth.

13. The method of producing an article of food, which consists in subjecting the food substance placed in proximity to the radiant energy of electric currents, utilizing therefrom the light, heat and actinic waves produced thereby, carrying off by artificially-dried and filtered air the moisture liberated by the heat energy of said currents, and finally pulverizing or grinding said substance, substantially as set forth.

In testimony whereof I have hereunto set my hand and affixed my seal this 1st day of August, 1896.
